CLAIM

The ornamental design for a wheeled multi-compartment receptacle, as shown and described.

DESCRIPTION

FIG. 1 is a perspective view of a wheeled multi-compartment receptacle showing our new design;

FIG. 2 is a front elevational view thereof;

FIG. 3 is a top plan view thereof, the bottom being plain and unornamented;

FIG. 4 is a left side elevational view thereof, the right side elevational view thereof being a mirror image; and

FIG. 5 is a rear elevational view thereof.

FIG. 1

FIG. 2

FIG. 3

FIG. 4

FIG. 5
